Patented Nov. 16, 1926.

UNITED STATES PATENT OFFICE.

JAMES LABANAUASKAS, OF WAUKEGAN, ILLINOIS.

VENTILATING APPARATUS.

Application filed March 26, 1925. Serial No. 18,512.

My invention relates to improvements in ventilating apparatus and has for one of its objects the production of a device of the kind, which is extremely neat and attractive in appearance, simple, convenient, compact, durable, reliable, efficient and satisfactory for use wherever found applicable. Many other objects and advantages of the construction herein shown and described will be obvious to those skilled in the art from the disclosures herein given.

To this end, my invention consists in the novel construction, arrangement and combination of parts herein shown and described, and more particularly pointed out in the claim.

In the drawings, wherein like reference characters indicate like or corresponding parts;

20 Fig. 1 is a vertical section through the apparatus embodying my invention, the same being shown installed in the wall of a chimney;

Fig. 2 is a section taken on line 2—2 of Fig. 1;

25 Fig. 3 is a section taken on line 3—3 of Fig. 1; and

Fig. 4 is an enlarged fragmentary section taken substantially on the same line as 30 Fig. 3.

The apparatus embodying my invention is particularly adapted for use in dwellings for ventilating kitchens, halls, basements, and the like. For the purposes illustrated, 35 I have shown the apparatus installed in a chimney, but it will be understood that I am limited to this use only in so far as defined in the appended claim.

Referring to the drawing, the reference 40 character 10 designates a chimney having a flue 11. A suitable aperture 12 formed in one wall of the chimney, which wall is also part of a kitchen or the like, is adapted to receive a sleeve 14 of any suitable form and material. In this instance, 45 I have shown the sleeve 14 as cylindrical and have provided it with an inwardly projecting annular flange 15, the purpose of which will presently appear. Projecting 50 into the sleeve 14 is an annular flange 17 formed integral with a plate 18, which is positioned against the outer side of the apertured wall. The outer side of the plate 18 is also provided with an annular flange 55 20 in which is pivotally mounted a closure member 22, the closure member 22 being

adapted to rest against the outer edge of the annular flange 20 when it is in its closed position. Pivotaly mounted in the inner end of the sleeve 14 is a closure member 24 60 which, when in its closed position, will abut against the annular flange 15.

Pivotaly mounted upon the inner surface of the sleeve 14 is a lever 25, one end of which is connected by a link 27 to the closure member 24, the link 27 being loosely pivoted in the lever 25 and in an eye 29 formed upon the closure member 24. The other end of the lever 25 is operatively connected to the closure member 22 by 70 a rod 30 and a relatively flexible strap 32, as shown. One end of the rod 30 is loosely pivoted in the lever 25 and the other end thereof is secured to one end of the strap 32 by means of rivets 33, or the equivalent. 75 The other end of the strap 32 is fastened, as at 34, to an arcuate cam surface 35 formed upon a hinged member 36, whereby the closure member 22 is pivotally mounted in the aforementioned flange 20. 80

The strap 32 is sufficiently flexible so that when the closure member 22 is brought from the position wherein it is shown in Fig. 3 to the position wherein it is shown in Figs. 1 and 4, the strap will be wrapped around the 85 arcuate surface 35 in such manner that the lever 25 will be rotated in a clockwise direction (Fig. 1). This rotation of the lever 25 will cause the link 27 to bring the closure member 24 from the position wherein it is 90 shown in Fig. 3 to the position wherein it is shown in Figs. 1 and 4. However, in the preferred form of my invention, the strap 33 has sufficient rigidity so that when the closure member 22 is brought into its closed position, the strap will not buckle, but will 95 push the rod 30 to rotate the lever 25 in a counter-clockwise direction (Fig. 1). This rotation of the lever 25 will cause the link 27 to bring the closure member 24 into the position wherein it rests against the annular flange 15. 100

A fan 37 may be rotatably mounted in a bar 37^a arranged transversely in one end of the passage through the sleeve 14 and the plate 18, the same indicating draft through the device. A small electrical motor (not shown) may be mounted in the sleeve to drive the fan, if so desired, and provide increased draft. 105

Any suitable means may be provided for locking the closure members in their closed 110

positions. I prefer to provide a pivoted latch member 38 upon the closure member 22 adapted to engage a keeper 39 formed in the flange 20. This insures that an undesirable draft through the room may be prevented at any time.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

In apparatus of the kind described and in combination, a passage open at its ends, a closure member for each end of the passage, means operatively connecting said closure

members whereby when one of said members is opened the other will be opened, said means comprising a lever mounted in the passage, a link operatively connecting the lever with one of the closure members, a flexible strap operatively connecting the lever with the other of the closure members, a cam on said last mentioned closure member, said strap being adapted to be wrapped about the cam when the closure member upon which it is mounted is opened whereby the lever is actuated to open the other closure member, said strap being sufficiently rigid that when it is unwrapped from the cam by shutting of the closure member upon which it is mounted said strap will force the lever in the opposite direction to shut the other closure member.

In testimony whereof I have hereunto signed my name.

JAMES LABANAUSKAS.
